Fig. 2.

Fig. 3.

FIGURE 1 is a front elevational view showing my new design for an archery target;

FIGURE 2 is a side elevational view of the target; and

FIGURE 3 is a plan view of the target.

The characteristic feature of my design resides in the combination on an archery target of three integral triangularly disposed ears about the periphery as shown.

I claim:

The ornamental design for an archery target, as shown and described.
